US00D732550S

(12) **United States Design Patent**
Westenberg et al.

(10) **Patent No.:** US D732,550 S
(45) **Date of Patent:** ** Jun. 23, 2015

(54) **DISPLAY DEVICE WITH GRAPHICAL USER INTERFACE**

(71) Applicant: **Symantec Corporation**, Mountain View, CA (US)

(72) Inventors: **Guido Westenberg**, Columbia Heights, MN (US); **Claudia Rudolph**, Medina, MN (US)

(73) Assignee: **Symantec Corporation**, Mountain View, CA (US)

(**) Term: **14 Years**

(21) Appl. No.: **29/439,767**

(22) Filed: **Dec. 14, 2012**

(51) LOC (10) Cl. **14-04**

(52) U.S. Cl. **USPC D14/485**

(58) **Field of Classification Search**

USPC D14/485-495
CPC G06F 3/048; G06F 3/0481; G06F 3/0482;

(57) **CLAIM**

The ornamental design for a display device with a graphical user interface, as shown and described.

DESCRIPTION

The FIGURE is a front view of a graphical user interface for a display device showing the claimed design.

The broken lines shown in the FIGURE illustrate portions of the graphical user interface and a display device that form no part of the claimed design.

1 Claim, 1 Drawing Sheet
